UNITED STATES PATENT OFFICE

HERBERT S. JANDUS AND EVERETT RUSH KEELOR, OF DETROIT, MICHIGAN, ASSIGNEES,
BY MESNE ASSIGNMENTS, TO GENERAL SPRING BUMPER CORPORATION, A CORPO-
RATION OF MICHIGAN

BUMPER CLAMP

Application filed July 18, 1927. Serial No. 206,437.

This invention relates to clamps for holding several bars in proper spaced relation and more particularly to a clamp adapted to be applied to the several bars of a vehicle 5 bumper.

An object of our invention is to provide a clamp which may be readily applied to the bumper bars and which will hold them rigidly in their proper spaced relation. A further 10 object is to provide such a clamp which can be economically constructed but which will have the necessary strength to withstand the shocks to which it may be subjected in service. A further object is to provide 15 such a clamp which will at the same time present an attractive appearance in conjunction with the remainder of the bumper. Further objects will be apparent from the description and drawings and from the use of 20 the articles covered by the claims.

In the drawings Fig. 1 represents a plan view of a bumper to the center of which our clamp has been applied; Fig. 2 shows a fractional front elevation of the central portion 25 of the bumper shown in Fig. 1, showing the clamp in detail; Fig. 3 shows a sectional view taken on line 3—3 of Fig. 2; Fig. 4 shows a rear elevation of the front plate of the clamp; Fig. 5 is a fractional front elevation of the 30 central portion of a bumper similar to that shown in Fig. 1, with a modified type of clamp attached thereto; Fig. 6 shows a sectional view taken on line 6—6 of Fig. 5; Fig. 7 shows a rear elevation of the front plate 35 shown in Fig. 5; Fig. 8 shows a fractional front elevation of the central portion of a bumper similar to that shown in Fig. 1 with a modification of our clamp attached thereto; Fig. 9 shows a sectional view taken on line 40 9—9 of Fig. 8; Fig. 10 shows a rear elevation of the front plate shown in Fig. 8.

Of the several reference characters 1 and 2 denote the impact bars of a bumper of the 45 general type shown in the McGregor Patent No. 1,372,154 issued March 22, 1921. This bumper has a rear bar 3 pivotally connected at its ends to the ends of the impact bars by means of pins 4, 4 and has its central portion bent forwardly and connected to the

central portion of the impact bars by means of our clamp.

The front plate 5 may be cast and is provided with a raised rib 6 extending around its periphery and adapted to bear on the front 55 surfaces of the bars 1 and 2. At the top and bottom extremities of this plate there are projecting portions 7 and 8 respectively which provide bearing surfaces for the upper edge of the impact bar 1 and the lower edge of the impact bar 2. The oppositely directed U-shaped lugs 9 and 10 project rearwardly from the rear surface of the plate 5 and each is covered by a portion having a slot 11 therein for the reception of the shank, and providing 60 a seat for the head, of a bolt 12, provided with a nut 16. The adjacent edges of the lugs 9 and 10 have depressions 13 and 14 respectively, providing seats for the edges of the rear bar 3.

The rear clamp plate 15 is adapted to bear 65 on the rear surface of the rear bar 3 and is bent forwardly at its end portions to a position adjacent the rear surfaces of the impact bars 1 and 2. This plate is provided with apertures for the reception of the shanks of bolts 12, 12.

In the modification shown in Figs. 5, 6 and 7 the front plate 5^a has the rearwardly projecting ribs 6^a extending around its periphery 80 and the portions 7^a and 8^a extending rearwardly therefrom to provide bearing surfaces for the edges of the impact bars 1^a and 2^a. The rearwardly projecting ribs, covered by the plates 17, 17 which have slots 11^a, 11^a 85 therein, provide recesses for the reception of the shanks of the bolts 12^a, 12^a and bearing surfaces for the heads of the said bolts. The rear plate 15^a is adapted to bear upon the rear surface of the rear bar 3^a and has holes 90 for the reception of shanks of the bolts 12^a, 12^a. With this front plate, the bars 1^a and 2^a are adapted to bear upon the rib 6^a and upon one of the plates 17, and the rear bar 3^a bears upon the plates 17, 17 and upon 95 the rib 6^a. By tightening the nuts on the bolts 12^a, 12^a the ends of the rear plate 15^a may be drawn into contact with the rear surfaces of bars 1^a and 2^a. In the modification shown in these figures the front surface of the lower 100

impact bar is in alignment with the front surface of the rear bar 3^a at the middle of the bumper and the rear bar curves rearwardly at each side of this point a sufficient amount so that the lower impact bar will pass in front of the rear bar where these bars overlap.

In the modified clamp shown in Figs. 8, 9 and 10 the rib 6^b projects rearwardly from the rear surface of the plate 5^b. The portion 8^b of this rib projects beyond the remainder of the rib to provide a bearing surface for the lower edge of the bar 2^b. The plate 18, integral with the upper edge of the rib 6^b and having a slot 11^b therein provides a bearing for the head of the bolt 12^b, the shank of such bolt passing through the said slot. The curved surface 19 bears upon the upper edge of the impact bar 1^b and so prevents an upward movement thereof. The projection 10^b similar to 10 of Fig. 4, provides a recess for the head of the bolt 12^b and has a slot 11^b for the shank of the said bolt. The impact bars 1^b and 2^b bear upon the opposite portions of the rib 6^b and are prevented from movement away from each other by the projecting portions 18 and 8^b. The rear bar 3^b is positioned behind and bears upon the rear surface of the impact bar 1^b. The rear plate 15^b is bent at its upper end to provide a bearing surface upon the rear surface of the impact bar 1^b and at its lower end to provide a bearing surface upon the rear surface of the impact bar 2^b; the central portion of this plate being adapted to bear upon the rear bar 3^b.

In assembling these clamps the shanks of the bolts are inserted within the slots provided in the lugs projecting from the rear surface of the front plate so that the heads of the bolts bear upon the bearing therein provided, and the said plate is then applied to the front surface of the impact bars. The rear plate is applied to the rear surface of the rear bar at such a position that the apertures in the said plate will receive the shanks of the bolts projecting from the front plates. By tightening the nuts on the bolts the several bars are held from relative movement.

The rear plates shown in Figs. 3 and 6 are shown as spaced at their end portions from the rear surfaces of the impact bars. These plates are preferably of relatively soft material which may be bent, by the pressure of the nuts on the bolts passing therethrough, to contact with the rear surfaces of the impact bars. It is apparent however that the rear plate may be initially bent to provide a surface adapted to bear upon the surfaces of these bars and it is not intended to herein limit our invention to a rear clamp plate of any particular shape. In each of the modifications shown the rear surface of the rear bar 3, 3^a or 3^b is in a plane spaced rearwardly from the rear surface of the impact bars.

This arrangement may be obtained either by using a rear bar which is thicker than the impact bars or by having the rear bar offset rearwardly.

The several modifications of our clamp show that the invention disclosed hereby can be incorporated into clamps adapted for bars having varying vertical displacement and it is also apparent that it can be applied to bumpers of types differing from that shown in the drawings. It is not intended to hereby limit its use to any particular type of bumper or to any particular position on the bumper; it being applicable wherever it is desired to clamp several bars together.

Having thus described our invention, what we claim is:—

1. The combination with a pair of spaced bars and an auxiliary bar, of a plate having portions projecting rearwardly and adapted to bear upon the front surfaces of said spaced bars, and having lugs, with substantially vertically extending portions, extending rearwardly therefrom, said lugs being adapted to bear upon the front surface of the auxiliary bar and having apertures in the vertically extending portions, a plate adapted to bear upon the rear surface of the auxiliary bar and means adapted to fit within said apertures for drawing said plates toward each other.

2. The combination with a pair of vertically spaced impact bars and a rear bar, of a plate having rearwardly projecting portions adapted to bear upon the front surfaces of the impact bars and rearwardly projecting lugs having substantially vertically extending portions with apertures therein, a rear plate adapted to bear upon the rear surface of a bar and means adapted to fit within the said apertures for drawing said plates toward each other.

3. The combination with a pair of spaced bars and a rear bar, of a plate having portions projecting rearwardly and adapted to bear upon the front surfaces of said bars, said plate also having portions adapted to bear upon the edges of the said spaced bars and having rearwardly extending lugs with substantially vertically extending portions having apertures therein, a plate adapted to bear upon the rear surface of the rear bar and means passing through said apertures for drawing said plates toward each other.

4. The combination with a pair of vertically spaced bumper bars and a rear bar, of a plate having projecting portions adapted to bear upon the front surfaces of the said spaced bars and a projecting portion adapted to bear upon the front surface of the rear bar, said last mentioned portion having an aperture therein adapted to receive the head of a bolt, a second plate adapted to bear on the rear surface of the rear bar and a bolt

- for drawing the said plates toward each other.
5. The combination with a pair of vertically spaced bars, of a plate having rearwardly projecting portions adapted to bear on the front surfaces of the bars and rearwardly projecting L-shaped portions having apertures in the portions substantially parallel to the said plate, a plate adapted to bear upon the rear surfaces of the bars, and means adapted to fit within said apertures for clamping the plates together. 10
6. A plate for a bumper clamp, said plate having rearwardly projecting portions at each side adapted to bear upon bars of a bumper, and a pair of rearwardly projecting portions having apertures therein to receive means for clamping the plate to the bars. 15
- 20 7. A plate for a bumper clamp, said plate having a projecting portion adapted to bear upon the front surface of a bumper bar, a projecting portion adapted to bear upon the edge of the said bar and a projecting portion having an aperture therein for the reception of means for clamping the plate to the bumper.
8. A plate for a bumper clamp, said plate having a projecting portion extending around its periphery and adapted to bear upon a bumper bar, and a projecting portion having an aperture therein for the reception of means for clamping the plate to the bumper. 30
9. A plate for a bumper clamp, said plate having projecting portions adapted to bear upon the front surface of a bar of the bumper and an L-shaped projecting portion having an aperture therein adapted to receive means for clamping the said plate to a bumper. 35
- 40 10. A plate for a bar clamp, said plate having projecting portions adapted to bear upon the surface of a bar and a projecting portion adapted to bear upon the surface of a second bar and providing a seat for means for clamping the plate to the bars. 45
11. A plate for a bumper clamp, said plate having projecting portions on each side, each adapted to bear upon the surface of a bar of the bumper and a projecting portion having an aperture therein and adapted to provide a seat for means for clamping the said plate to the bumper. 50
- 55 12. A plate for a bumper clamp, said plate having a projecting portion adapted to bear upon a bar of the bumper and a projecting portion having an aperture therein adapted to provide a seat for means for clamping the said plate to the bumper.
- 60 13. The combination with a pair of spaced bars, of a plate adapted to bear upon the front surfaces of said bars, said plate having a rearwardly projecting apertured lug shaped to provide a seat at the rear of the plate for the head of clamping means, a rear plate adapted 65 to bear upon the rear surfaces of said bars and clamp means passing through the aperture in said lug and between said bars to draw said plates toward each other.
14. The combination with a pair of spaced bars, of a plate adapted to bear upon the front surfaces of said bars, said plate having a rearwardly projecting apertured lug shaped to provide a seat at the rear of the plate for the head of clamping means, and a rearwardly projecting surface adapted to bear upon an edge of one of said bars, a rear plate adapted to bear upon the rear surface of one of said bars, and clamping means passing through the aperture in said lug and between said spaced bars to draw said plates toward each other. 70
- 75 15. A clamp plate having a surface adapted to bear upon the surface of a bar to be clamped, said plate having a rearwardly extending arched lug with an aperture in its middle portion. 80
- 85 16. A clamp plate having a surface adapted to bear upon the surface of a bar to be clamped thereby, said plate having a rearwardly extending arched lug, closed at one end and having an aperture in its middle portion. 90
- 95 17. The combination with a pair of bumper bars adapted to be clamped together, of a clamp plate having a surface bearing upon the front surface of one of said bars, said plate having an arched portion projecting from its rear surface with an aperture in said arched portion, a rear plate adapted to bear upon the rear surface of one of said bars, and clamping means for drawing said plates toward each other. 100
- 105 18. The combination with a pair of vertically spaced impact bars and an auxiliary bar to be clamped thereto, of a clamp plate adapted to bear upon the front surfaces of said spaced bars, said clamp plate having an arched lug projecting from its rear surface with an aperture in the middle portion of said lug, a rear plate adapted to bear upon the rear surface of said auxiliary bar, and means passing between said impact bars for drawing said plates together. 110
- 115 19. The combination with a pair of vertically spaced impact bars and an auxiliary bar to be clamped thereto, of a clamp plate adapted to bear upon the front surfaces of said spaced bars, said clamp plate having a rearwardly projecting portion adapted to bear upon an edge of said impact bars and an arched lug, having an aperture in its middle portion, projecting from the rear surface of said plate, a rear plate adapted to bear upon the rear surface of one of said bars and means, passing between said impact bars, for drawing said plates toward each other. 120
- 125 20. The combination with a pair of vertically spaced impact bars and an auxiliary bar adapted to be connected thereto, of a plate adapted to bear upon the front surfaces of said impact bars, said plate having rearward- 130

- ly projecting lugs adapted to bear upon the outer edges of said impact bars and having rearwardly projecting arched lugs with apertures in their middle portions, a rear plate 5 adapted to bear upon the rear surface of said auxiliary bar and means, passing between said bars and through said apertures, for drawing said front and rear plates toward each other.
21. A clamp plate for securing bars against 10 movement relative to each other, said plate having portions adapted to bear upon the front surfaces of the bars, projecting portions adapted to bear upon the edges of the said 15 bars, and projecting lugs having portions extending substantially parallel to the said bars, said last mentioned portions having apertures for the reception of suitable clamping means for drawing said plate toward the 20 front surfaces of said bars.
22. A clamp plate for securing bars against 25 movement relative to each other, said plate having rearwardly projecting portions adapted to provide bearing surfaces for the front surfaces of said bars, and having apertured portions connecting said projecting 30 portions and adapted to provide seats spaced rearwardly from the plate for the reception of suitable clamping means.
23. A clamp plate for securing vertically 35 spaced bars of a vehicle bumper, said plate having marginal flanges adapted to bear upon the front surfaces of said spaced bars, said marginal flanges having inwardly projecting portions opposite the space between said bars and adapted to provide a seat between said projections and the rear surface of said plate for the reception of suitable clamping means.
- 40 In testimony whereof, we hereunto affix our signatures.

HERBERT S. JANDUS.
